CLAIM

The ornamental design for a cigar, as shown and described.

DESCRIPTION

FIG. 1 is a perspective view of a cigar according to my new design;

FIG. 2 is a rear elevation view of FIG. 1;

FIG. 3 is a front elevation view of FIG. 1; and,

FIG. 4 is a left side elevation view of FIG. 1. The right side elevation view and the top and bottom plan views are mirror images of FIG. 4.
